UNITED STATES PATENT OFFICE

GEORGE LOOP MOORE AND JAMES ROBERT STEELE, OF OWEGO, NEW YORK

RAIL ANCHOR

Continuation of application Serial No. 401,392, filed October 22, 1929. This application filed July 31, 1930.
Serial No. 471,947.

Our invention relates to rail anchors and particularly to a one-piece double acting type constructed to engage one edge of a rail base flange on opposite sides of a tie and to be fulcrumed at an intermediate point to prevent the longitudinal creeping of the rail in either direction by the traffic moving over it.

An object of our invention is to provide a rail anchor formed of a single piece of metal which is easily applied to the rail base, efficiently grips the same, and cooperates with a stationary member of the road bed to prevent the rail from creeping.

Another object of our invention is to provide a rail anchor, which is applied to a railroad rail by distortion and will be held in operative position by the tendency of the anchor to resume a condition from which it was sprung when applied to the rail.

A further object of our invention is to provide an improved one-piece rail anchor adaptable to rails having base flanges of different widths.

Another object of our invention is to provide a one-piece rail anchor which will check the longitudinal creeping of the rail in either direction of traffic.

Another object of our invention is to provide a one-piece two-way acting rail anchor which does not depend upon a cross tie abutment to check the creeping of the rail.

The novel features of our invention will be more fully understood from the following description and claims taken with the drawings, in which:

Fig. 1 is a plan view of one form of our improved rail anchor;

Fig. 2 is a front elevation of the anchor shown in Fig. 1;

Fig. 3 is a view of one end of the anchor as shown in Fig. 2;

Fig. 4 is a section taken on line 4—4 of Fig. 2;

Fig. 5 is a view of a portion of a railroad rail, a cross tie supporting the rail, a spike securing the rail to the tie and the rail anchor in its initial and operative positions on the rail;

Fig. 6 is an end view of the anchor in operative position on the rail.

Figs. 7, 8, 9, 10 and 11 are similar to Figs. 1, 2, 3, 4, and 5 but illustrating a modified construction of the anchor.

Fig. 12 shows the manner in which a claw bar is used when applying the anchors shown in Fig. 1 to 11 inclusive.

Figs. 13, 14, 15, 16 and 17 are similar to Figs. 1, 2, 3, 4 and 5 but illustrating a modified construction which is adapted to be driven onto a rail.

Fig. 18 shows a modification to the end of the anchor shown in Figs. 16 and 17.

Referring to the drawings: 15 indicates a rail, 16 a cross tie, 17 a spike, and 18, 19 and 20 the respective forms of rail anchors.

In the embodiment of our invention shown in Figs. 1 to 6, inclusive, the anchor comprises end members 21 and 22 and an intermediate connecting member 23, which is adapted to bridge a tie.

The anchor is preferably made from a rectangular bar of resilient metal of uniform section and its ends are formed with notches 24 and 25 to provide rail engaging members 26 and 27. The said members are formed so as to engage the bottom of the rail adjacent the edge of one of the rail base flanges.

The connecting member 23 is preferably formed with a pocket or depression 28 which is adapted to fit over the head of the spike 17 and thus retain the anchor in its operative position as shown in Fig. 5. The pocket may be formed by depressing the material on both sides of the spike head to form abutments 29 which prevent the longitudinal displacement of the anchor when it is in its operative position as shown in Fig. 5. It will be noted from Figs. 1 and 4 that the abutments 29 on either side of the spike head extend but part way across the member 23, and that a lip 30 is formed which extends inwardly towards the rail over the head of the spike to prevent dislodgement of the anchor when it is in its operative position.

From the Figs. 2 and 6 it will be seen that the end member 22 is bent outwardly and upwardly and is formed with an inclined cam face 31 which is adapted to provide an

abutment for a claw bar 32 by means of which the anchor may be applied to the rail.

It will be noted that the distance between the spike bearing portion 28 and the end member 21 is less than the distance between the portion 28 and the end member 22 and that the notch 24 is nearer the underside of member 23 than the notch 25. It will therefore be obvious that when the anchor is initially positioned on the rail, as shown in Fig. 5, that the end member 22 will assume the position as shown by the dotted lines and when the end member 19 is forced downwardly by means of the claw bar, the member 23 is sprung thereby setting up reactions between the head of the spike and the point of engagement at the end 21 and the underside of the rail base and the end 22 and the underside of the rail, the gripping forces being greater at end 21 than at 22, due to the location of the bearing point 28. The increase of force brings heavy pressure to bear upon the head of the spike and provides efficient anchorage to the road bed through the medium of the cross tie. 25 and when the anchor is finally positioned the pocket, formed by the depressions on both sides of the spike head, prevents the longitudinal displacement of the anchor relative to the cross tie.

30 The anchor is applied to a rail by hooking the notch 24 over one flange of the rail base and bringing portion 28 into engagement with the head of the spike. A trackman claw bar 32 is now inserted between the space provided by the underside of the rail and portion 35 of the end member 22. A downward movement of the end of the claw bar forces end 22 downwardly until notch 25 is in line with the edge of the rail base and further movement of the claw bar forces the rail engaging member 27 into engagement with the flange of the rail due to the shape of portion 35 which acts as a cam. This is best illustrated in Fig. 12 of the modified form the method of application being the same for the species shown in Figs. 2 and 10, respectively.

In Figs. 7 to 12 inclusive we have illustrated a modified embodiment. In this modification the general features and principle of action and application are the same as for the anchor as shown in Figs. 1 to 6 inclusive, the principal differences being the manner in which the abutments are formed for the spike head on member 37. In this case the depressions 38 are carried the full width of the bar 37 to form projections 39 on both sides of the head of the spike. The pocket 40 so formed brings the bearing portion for the head of the spike in line with the underside 41 of member 37. The notches 42 and 43 which constitute rail engaging means of members 44 and 45, respectively, of portions 46 and 47 are substantially parallel with the member 37 instead of being in different planes as shown in Fig. 2. The end 48 of portion 47

is bent outwardly and twisted relatively to 47 to form an abutment for the claw bar as shown in Figs. 9 and 12.

As heretofore stated, the method of application of the modified form as shown in Fig. 8, is the same as for the form shown in Fig. 2.

To release the anchor from the rail, a claw bar is used to pry the rail engaging members 27 or 45 from the base of the rail thereby releasing the grip of the anchor and allowing it to return to its unsprung condition.

In Figs. 13 to 18, inclusive, we have illustrated another modified embodiment. In this modification the principal difference in this anchor from those previously described is that this anchor is adapted to be driven onto the rail with a blow of a hammer at the point indicated by the arrow in Fig. 17, instead of being pulled on by a tool.

This anchor is preferably made of material similar to that previously described but the tool engaging members 35 or 48 of the anchor are dispensed with and preferably either a curved surface 50, Fig. 15, or a step 51, Fig. 18, is provided to assist in applying the anchor to its operative position and also to prevent the anchor from springing directly upwardly during removal from a rail.

Preferably the notches 52 and 53 are so shaped that when the anchor is applied to a rail the members 54 and 55 will grip the rail on one side of the tie and the members 56 and 57 will grip the rail on the other side of the tie although these recesses may be made similar to those shown on the first described anchors. The connecting member 58 is preferably provided with a pocket 59 to receive the head of a track spike.

The anchor is applied to a rail by hooking the notch 52 over one flange of the rail base and bringing the portion 59 into engagement with the head of the spike. If the notch 52 is shaped so that the members 54 and 55 grip the rail flange, this end of the anchor is struck a blow on the side so that the members 54 and 55 are driven into gripping relation with the rail. The anchor is now in the position indicated by dotted lines Fig. 17. Pressure is now applied to the other end of the member 58, such as by placing the foot thereon and a downward blow is struck with a hammer at the point indicated by the arrow in Fig. 17. If the member 57 of the anchor is curved as indicated in Fig. 15 the rail flange will enter the notch 53 and the members 56 and 57 can be brought into gripping engagement with the rail flange by a light blow of the hammer on the outer side of the anchor adjacent these members. If the member 57 is provided with a step 51 the initial blow of the hammer is preferably such that the step engages the flange of the rail and an additional blow is required to bring the mem-

bers 56 and 57 into initial engagement with the rail flange.

From the foregoing description it will be obvious to those skilled in the art that we have devised an improved one-piece rail anchor which is simple in construction, easily applied to the rail base and efficiently grips same to check the creeping tendency of the rail in either direction of travel. Our device is particularly adaptable to rails having base flanges of different widths as it grips only one side of the flange of a rail its gripping ability is not affected by changes in widths of base flanges.

Another feature of importance is the fact that the anchor does not depend upon the cross tie for abutment as do the majority of other rail anchors, therefore there is no cutting or working away from the tie to render it ineffective due to the movement of the rail relative to the tie, as our anchor grips the head of the spike instead of abutting the tie.

While we have shown our invention in a plurality of forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

Having thus described our invention what we claim as new and desire to secure by Letters Patent is:

1. A rail anchor comprising spaced members adapted to engage one edge of a rail base, a connecting member for said spaced members adapted to bridge a tie and means associated with said connecting member adapted to engage the head of a track spike.

2. A rail anchor comprising rail base engaging members and a spike engaging portion having abutments adapted to engage the head of a track spike when said anchor is in its operative position on a rail.

3. A rail anchor comprising rail base engaging members adapted to grip one edge of a rail base and a track spike engaging portion adapted to grip the head of a spike when said anchor is in its operative position on a rail.

4. A rail anchor comprising rail base engaging members and a spike engaging portion having lateral abutments adapted to engage the head of a track spike when the anchor is in its operative position on a rail, and means to prevent dislodgment of the anchor from its operative position.

5. A rail anchor comprising depending end portions adapted to grip one edge of a rail base, a member connecting said end portions, a depression in said connecting member adapted to engage the head of a track spike and means on one of said ends adapted to be engaged by an applying tool.

6. A rail anchor comprising depending end portions adapted to grip one edge of a rail base, a member connecting said end portions, a depression in said connecting member adapted to engage the head of a track spike.

7. A rail anchor comprising depending members formed with rail engaging shoulders adapted to engage one flange of a rail base, a resilient member connecting said depending members and adapted to bear with spring pressure against a stationary member of the road bed.

8. A rail anchor comprising depending members formed with rail engaging members adapted to engage the underside of a rail base at one side of a rail, a resilient member connecting the upper ends of said depending members, said connecting member being adapted to engage the head of a track spike and to be distorted when applied to a rail to effect a gripping action between said rail engaging members and the base of the rail and said connecting member and said spike.

9. A rail anchor comprising depending members formed with rail engaging shoulders adapted to engage one flange of a rail base, a resilient member connecting said depending members and adapted to bear with spring pressure against a stationary member of the road bed, said depending members being positioned on opposite sides of a cross tie when in operative position on a rail.

10. A rail anchor comprising a resilient member adapted to extend over a railway cross tie and having downwardly turned ends adapted to engage the flange of a rail base, said resilient member having a depressed portion adapted to receive the head of a track spike, said depressed portion being unequally spaced intermediate said ends, and means on one of said ends adapted to be engaged by an applying tool.

11. A rail anchor comprising a resilient member adapted to extend over a railway cross tie and having downwardly turned ends adapted to engage the flange of a rail base, said resilient member having a recessed portion adapted to receive the head of a track spike.

12. A rail anchor comprising a resilient member adapted to extend over a railway cross tie and having downwardly turned ends adapted to engage the flange of a rail base, said resilient member having a depressed portion adapted to receive the head of a track spike and said depressed portion being unequally spaced intermediate said ends.

13. A rail anchor comprising a resilient member adapted to extend longitudinally over the base of a rail, and downwardly turned ends having members adapted to engage the bottom of a rail base flange at one side of the rail, said resilient member having means adapted to grip the head of a track spike and to lock said depending members.

to said base flange during the application of the anchor to a rail.

14. A rail anchor comprising a resilient member adapted to extend longitudinally over the base of a rail and crosswise of a tie and having downwardly turned notched portions extending beyond the base of the rail, said resilient member having a portion adapted to grip the head of a track spike and so positioned relative to said notched portions to provide a clearance between the tie and said notched portions when in operative position on a rail.

15. In a rail anchor, spaced rail gripping members for engaging one flange of a rail base and means provided intermediate said gripping members for exerting a pressure vertically of the rail on a fixed member of the road bed to maintain said gripping members in gripping position on the rail.

16. A rail anchor comprising spaced rail engaging members for engaging one flange of a rail base on opposite sides of a cross tie and provided with a portion arranged between and connecting said rail engaging members and so disposed with relation to said rail engaging members as to be depressed from its normal position during the application of the anchor to a rail.

17. In a rail anchor, spaced rail gripping members for engaging one flange of a rail base on opposite sides of a cross tie, a connecting member intermediate said gripping members provided with abutments adapted to coact against a fixed member of the road bed, said gripping members being so disposed relative to said connecting member as to effect a gripping action between said members and the rail.

18. A rail anchor comprising downwardly disposed members for engaging one flange of a rail base, and an intermediate member adapted to extend above the base of the rail connecting said members, said intermediate member having spaced abutments adapted to coact with the head of a track spike and positioned nearer to one of said members than to the other, and an outwardly extending ledge portion formed at the lower end of one of said members and having an inclined face adapted to be engaged by a trackman's claw bar.

19. A rail anchor for rails, comprising a plurality of rail base engaging members adapted to engage one edge of the rail base, and means connecting the ends of said members adapted to engage the head of a track spike.

20. A rail anchor for rails, comprising a plurality of rail base engaging members adapted to engage one edge of the rail base, and means connecting the ends of said members adapted to engage the head of a track spike whereby said anchor is applied to a rail to effect a gripping and holding action be-

tween the rail engaging members and the underside of the rail base.

21. A one-piece rail anchor for rails adapted to straddle a fixed element of the road bed and to grip one edge of the rail base flange and the head of a track spike which comprises an element of the road bed when in operative position.

22. A one-piece rail anchor for rails adapted to straddle a cross tie and to grip one edge of the base flange and coact with the head of a track spike when operatively applied thereto.

23. A one-piece rail anchor for rails having a plurality of members adapted to grip one edge of the rail base, means connecting said members and adapted to contact with the head of a track spike, whereby the anchor will be held in frictional engagement at two points on the rail and at a third point comprising said spike when in operative position.

24. In combination with a railway cross tie, a rail in position thereon and spikes for retaining the rail in position upon the tie, a rail anchor having rail engaging members adapted to frictionally engage one edge of the rail base at opposite sides of the tie and another member having a depression adapted to engage the head of a spike to constantly exert downward pressure on said spike toward the tie and to resist movement of said anchor relative to said tie.

25. In combination with a railway cross tie, a rail in position thereon and spikes for retaining the rail in position upon the tie, a one-piece anchor having rail engaging members adapted to frictionally engage one edge of the rail base at opposite sides of the tie, and a connecting member having a depression adapted to engage the head of a spike to constantly urge same toward the tie when one of said rail engaging members is moved downwardly to flex said connecting member whereby a gripping action between the anchor and the rail is effected.

26. A one-piece rail anchor comprising spaced rail engaging members, means connecting said members adapted to bridge a tie and means connected to said connecting means adapted to engage a relatively stationary member of the road bed whereby the rail engaging members are retained in frictional engagement with the rail.

27. A rail anchor adapted to be driven onto a rail comprising depending notched end portions adapted to grip one edge of a rail flange and a connecting member for said end portions adapted to bridge a tie and engage the upper surface of the head of a track spike.

28. A rail anchor adapted to be driven onto a rail comprising depending end portions adapted to grip one edge of a rail base and a connecting member for said end portions

adapted to engage the head of a track spike so as to exert a downward pressure thereon.

29. A rail anchor comprising rail engaging members adjacent each end thereof and an intermediate member connecting said members said intermediate member having means for engaging the head of a spike and said rail engaging members having notches constituting shoulders adapted to engage the flange of a rail one of said shoulders having a portion thereof removed at its outer edge.

30. A rail anchor comprising a portion adapted to fulcrum on a member of a track structure intermediate the edges of a tie and depending end portions having shoulders adapted to engage the base of a rail at either side of the tie.

31. A one-piece rail anchor comprising a portion adapted to fulcrum on a member of a track structure intermediate the edges of a tie and end portions having shoulders adapted to engage the base of a rail.

32. A rail anchor comprising rail base and track spike engaging portions, said anchor to be applied to the rail by distortion and held in operative position on the rail by the tendency of the anchor to resume the condition from which it was sprung, said anchor being adapted to engage but one side of the rail base.

33. In a rail anchor, spaced rail gripping members for engaging one flange of a rail base on opposite sides of a cross tie, a connecting member intermediate said gripping members provided with abutments adapted to coact against a fixed member of the road bed, said gripping members being so disposed relative to said connecting member as to require distortion of said connecting member to effect a gripping action between said members and the rail.

34. A rail anchor for rails, comprising a plurality of rail base engaging members adapted to engage one edge of the rail base, and means connecting the ends of said members adapted to engage the head of a track spike, whereby said connecting member is sprung when said anchor is applied to a rail to effect a gripping and holding action between said members and the underside of the rail base.

35. A rail anchor comprising a plurality of rail engaging members and a member to pass over a spike head and having a pocket receptive of said spike head.

36. A rail anchor comprising a resilient member adapted to bridge a railway cross tie and downwardly turned end members adapted to engage the flange of a rail base, said resilient member having a depressed portion to provide a pocket for a spike head.

In testimony whereof we hereunto affix our signatures.

GEORGE LOOP MOORE.
JAMES ROBERT STEELE.
